UNITED STATES PATENT OFFICE.

EUGENE J. DALEY, JR., OF SAN FRANCISCO, CALIFORNIA.

DESIGN FOR A GAME-BOARD.

• 57,036.

Specification for Design.

Patented Feb. 1, 1921.

Application filed August 23, 1920. Serial No. 405,519. Term of patent 14 years.

To all whom it may concern:

Be it known that I, EUGENE J. DALEY, Jr., a citizen of the United States, residing at 2405 18th street, in the city and county of San Francisco, State of California, have invented a new, original, and ornamental Design for a Game-Board, of which the following is a specification, reference being had

to the accompanying drawing, forming part thereof.

The figure is a plan view of the game board, showing my new design.

I claim:

The ornamental design for a game board, as shown.

EUGENE J. DALEY, JR.
